DISPENSER

Filed April 14, 1934

UNITED STATES PATENT OFFICE

2,017,133

DISPENSER

Frank E. Rice, Detroit, Mich., assignor to American Tap-Bush Company, Detroit, Mich., a corporation of Michigan

Application April 14, 1934, Serial No. 720,503

6 Claims. (Cl. 225—3)

The present invention relates to dispensers and will be described herein as a dispenser for small kegs and barrels of liquor, such as beer, commonly known as eighth barrels, or kegs.

5 Eighth barrels or kegs are utilized by home owners for dispensing barreled beer in small quantities. It is disadvantageous for home owners to provide themselves with the usual tapping mechanism such as employed by bars and 10 the like for dispensing beer in large quantities.

The present invention is directed to combination of an eighth barrel or keg and a dispenser which dispenser is applied to the keg at the brewery and supplied with the keg delivered to 15 the user at his home, which dispenser may be utilized for the drawing of beer from the keg in small amounts.

20 The assembly of the present invention contemplates a collapsible faucet which is folded against a head of the keg in position to be free of damage or harm by reason of the handling of the keg and which may be extended for use for discharging the contents of the keg. In 25 utilizing the dispenser of the present invention, it is necessary only to break the seal and open the valve for discharging the contents of the keg.

An object of the present invention is to provide dispensers for eighth barrels which may be applied to the barrels at the brewery and supplied 30 with the barrels to the consumer and which dispensers are readily adaptable for use when desired.

35 Another object of the invention is to provide a dispenser for a beer keg so constructed as to be movable out of the way when not in use and to be extended for use when desired.

40 A further object of the invention is to provide a dispenser for beer kegs and the like which is economical to manufacture and efficient in use, and which may be readily applied to or removed from a keg by a simple twisting movement.

45 A still further object of the invention has to do with the provision of a novel dispensing valve structure for beer barrels and the like. Generally speaking the dispenser of the present invention contemplates one which may be used in conjunction with a tap bush of well known form and which dispenser is provided with means whereby pressure may be created within the keg, together with valve means for controlling outflow of the contents of the barrel when desired.

50 An embodiment of the present invention is illustrated in the accompanying drawing and the views thereof are as follows:

Figure 1 is a top plan view of an eighth keg provided with the dispenser of the present invention, showing in full lines the dispenser in collapsed position, and in dotted lines two positions of the spout for dispensing purposes. 5

Figure 2 is a fragmental vertical sectional view through an eighth keg showing the dispenser of the present invention thereon in extended position for discharging the contents of the keg.

Figure 3 is a vertical sectional view taken substantially in the plane of line III—III of Figure 2. 10

Figure 4 is a longitudinal vertical sectional view through the valve body and valve barrel of the illustrated form of dispenser.

The drawing will now be explained: 15

An eighth keg or barrel 1 is illustrated as constructed of wood although, of course, the present dispenser is as applicable to a steel keg as to a wooden keg.

20 A head 2 is provided with a tap bush 3 of well known form, that herein illustrated being the well known "Peerless" tap bush. The faucet or dispenser structure comprises a valve body 4 having a bore through it which is illustrated as tapered as at 5. The bore extends from end to end of the head portion of the valve body. A boss 6 is formed as part of the valve body and is threaded at 7 to engage the threaded portion of a bottom lug member 8 which is adapted to cooperate with the tap bush 3 in securing the dispenser to a keg. The boss 6 is provided with an extension 9 and the boss and extension are formed with a bore or passageway 10 through it, which bore communicates with the bore 5 of the valve body 4. Alongside of and spaced from the bore 10 is another and smaller bore 11 passing through the boss and extension 9 and which is spaced axially with respect to the bore 10. 30 This bore 11 also communicates with the bore 5 of the valve body and opens through the inner 35 end of the extension 9 of the boss. 40

A pipe or rod 12 is secured in the extension 9 and communicates with the bore 10 and is illustrated as in threaded engagement with the extension. The rod or pipe 12 is provided with a 45 slide or movable fitting 13 at its lower end which fitting is closed at its bottom as at 14 and which fitting is provided with an aperture 15 through which the contents of the keg may enter the rod or pipe 12. Fitting 13 is provided with a slot 16 50 which cooperates with a pin 16^a on the rod 12 for maintaining the parts in association and a suitable spring, not shown, is interposed between the extremity of the rod 12 and the inner face of the end 14 of the fitting 13 so that this fitting 55

is at all times in its lowermost position with respect to the end of the rod 12. The purpose of the slideable fitting is to accommodate the rod to eighth kegs of varying heights to assure, at all times, that the lower end of the fitting is against the bottom of the keg to assure withdrawal of all of the contents of the keg through the rod 12.

The under side of the valve body 4 is provided with a swivel washer 17 suitably secured in position and which washer on its under face is concave. The swivel washer 17 engages against a sealing ring 18 surrounding the extension 9 of the valve body 4 and which is adapted to engage against the upper surface of the collar portion 15 of the tap bush 3 in the usual manner. The valve body 4 is attached to the tap bush 3 by means of the bottom lug member 8 whereupon the body member 4 is screwed toward the tap bush to tighten the valve body against the bush 20 and thus assure a leak tight joint between the valve body and the bush. During such action the concave surface of the swivel washer 17 tends to bend the sealing ring 18 against the curved upper surface of the collar or neck of the tap bush and thus increase the sealing effect at this point. The sealing member 18 is dished when the parts are connected together for use.

Within the bore 5 of the valve body 4 is a valve member 19, tapered to conform to the taper of the bore 5. Extending inwardly from the larger end of the taper is a bore 20 and extending inwardly from the opposite end of the valve member 19 is another bore 21. The bores 20 and 21 are axially separated by means of a partition 22 thus maintaining these bores out of communication with each other.

The extremity of the valve member 19 adjacent the smaller end is threaded to receive a nut 23 which bears against a spring-like washer 24 which in turn bears against a disc washer 25 for maintaining the valve member 19 in position in the valve body 4. Secured to the barrel valve member 19 outwardly of the smaller end thereof is an air valve 26 of the character of a bicycle tire valve which is closed by a cap 27 of well known form.

The barrel valve member 19 is provided with a port 28 extending laterally from the bore 21 and opening through the surface of the valve member 19 while another port 29 is formed in the valve member 19 to afford communication between the bore 20 of the valve member and the bore 10 of the valve body 4. The ports 28 and 29 are axially spaced with respect to each other and also angularly spaced with respect to each other.

The ports 28 and 29 are angularly or circumferentially spaced in such manner that when either port is in flow communication with its bore 11 or 10 in the valve body, the other port is out of flow communication with its body bore. At no time are both ports 28 and 29 in flow communication between the interior of the keg and the axial bores 21 and 20 of the valve member 19. Normally, when beer-flow communication between the interior of the kegs and the spout 35 is shut off or stopped, that is, when the valve member 19 is in the position illustrated in Figure 4, the port 28 is in flow communication between its member bore 21 and the body bore 11 so that if pressure is needed within the keg, all that has to be done is to remove the cap 27 from the air valve 26, apply a hose to the valve and admit air under pressure, or gas under pressure, to the interior of the keg without having to ac-

tuate the valve member 19. As soon as rotative movement is imparted to the valve member 19, in direction to open beer-flow communication between the spout 35 and the interior of the keg, the port 28 is moved out of register with its body bore 11, thus closing air communication between the air valve 26 and the interior of the kegs.

Attached to the barrel valve member 19 adjacent the larger end of the taper thereof is a handle member 30 adapted for oscillating the barrel 10 valve member in the valve body 4. The valve member is extended as at 31 to receive an elbow 32. A nippie 33 connects the elbow 32 with another elbow 34 on the inner end of a spout 35 so that the spout may have swinging movement about an axis perpendicular to the axis of the barrel valve member 19 and at the same time the valve member 19 may be swung about its axis.

Figure 1 illustrates the collapsed position of the dispenser, in which position the beer-flow outlet 20 is closed. This position results from moving the handle 30 from substantially vertical position such as that of Figure 2 to substantially horizontal position as in Figure 1 which thus swings the barrel valve member 19 about its axis within the 25 valve body 4 to move the port 29 out of communication with the bore 10 of the valve body thus closing the beer exit from the keg. The spout 35 is then swung to lie along side of the valve body 4 as shown in full lines in Figure 1 in which 30 position all of the parts of the dispenser lie below the top margin of the chime of the barrel and thus are protected against damage incidental to handling of the keg or barrel. When in this collapsed position, the spout may be sealed against 35 unauthorized movement as, for instance, by a wire 36 passed about the spout and through an opening in a pin 37 secured in the head of the barrel and through an opening 38 in the cap 27 of the air valve. A suitable seal 39 may be used 40 to fasten together the ends of the wire. If desired, a revenue stamp or other seal might be pasted over the spout in collapsed position. In either event, the seal has to be broken before the spout 35 can be moved to dispensing position 45 which is that shown in full lines in Figure 2 or dotted lines in Figure 1.

When it is desired to dispense beer from a keg equipped with the dispenser of the present invention, the seal 39 is broken, the wire 36 removed, and the cap 27 removed from the air valve whereupon an air hose from a pump is applied and pressure created within the keg. When sufficient pressure has been created the cap is replaced thus making ready the dispenser for use. 55 When it is desired to dispense beer from the keg, the handle 30 is actuated to swing the barrel valve member 19 about its axis so that the spout 35 in turn may be swung with its discharge end outwardly of the margin of the barrel whereupon 60 the completion of the movement of the barrel valve 19 to such position as will bring its port into communication with the bore 10 of the valve body 4 thereby establishing communication between the interior of the barrel and the spout 35 65 whereupon the beer will be discharged because of the presence of pressure within the keg. As soon as the receptacle is filled, the handle 30 is operated to close the bore 10 against further beer discharge. This actuation of the barrel valve 19 is effected as long as any beer remains in the keg. When the keg is empty, the valve may be collapsed and returned to the full line position of Figure 1 whereupon the keg is returned to the brewery for refilling. The dispenser of course, 70

accompanies the keg and remains fixed thereto at all times.

A handle 40 is illustrated as secured to a head of the barrel for lifting and carrying it.

5 It will be observed that the present invention contemplates a faucet or valve structure applicable to a tap bush of a beer barrel for closing the bush in lieu of the usual cork and which structure is adapted to receive an air hose connection for creating pressure within the barrel, also adapted to dispense the contents of the barrel by reason of the presence of such air pressure.

10 The closure structure enters into combination with a barrel or keg in such manner as to serve as a permanent closure for the tap bush and at the same time provide means whereby the contents of the keg or barrel may be readily withdrawn after sufficient pressure has been created by a pump or like instrumentality, or air or gas 15 has been applied through the structure of the present invention.

15 The invention has been described herein more or less precisely as to details, yet the invention is not to be limited thereby as changes may be made in the arrangement and proportion of parts, and equivalents may be substituted without departing from the spirit and scope of the invention.

The invention is claimed as follows:

20 1. In combination, an eighth keg having a tap bush in one head, a dispensing faucet structure connected to said bush, said structure comprising a lug member for engaging said bush, a valve body engaging said lug member, said valve body having a tapered bore extending through it and having a boss with two passages through it communicating with said bore in axially spaced relation to each other, a tapered ground barrel valve member in said tapered bore, said valve member having an endwise bore extending inwardly from the larger end and another endwise bore extending inwardly from the smaller end and a partition axially separating said bores, said valve member having a port for establishing communication 25 between said first bore and one of the passages in said boss and having another port for establishing communication between said second bore and the other of said passages in said boss, said ports being axially and also angularly spaced from each 30 other circumferentially of said barrel, an elbow connected to said barrel adjacent the larger end thereof, a spout swiveled to said elbow, an air valve connected to the barrel adjacent the smaller end thereof and communicating with the valve member bore at that end of said valve member, a pipe or rod connected to said boss communicating with said one passage thereof, a handle connected to said member for oscillating it, movement of said valve barrel in one direction establishing communication between the bore from the 35 smaller end of said barrel and the interior of the keg through said other passages in said boss and closing communication between said other valve member bore and said one passage in said boss, movement in the opposite direction closing communication between the first bore in said valve member and opening communication between the rod or pipe and the valve member bore from the larger end of said barrel for discharging beer through the spout.

40 2. A beer barrel assembly including a keg and a dispensing faucet structure removably attached to one head of the keg; said structure including a body having a bore in it and having dual passageways opening into the bore for flow communication with the interior of the keg;

45 nication with the interior of the keg; a valve member oscillatable in said bore, said valve member having two axially spaced and extending bores in it, one opening through one end of said member and the other opening through the other end of said member and being out of communication with each other; said valve member also having ports from said member bores opening through the side surface of said member and being circumferentially spaced whereby one of said 50 ports is movable into and out of register with one of said dual passageways, and the other of said ports is movable into and out of register with the other of said dual passageways; the arrangement being such that when either port and its member bore are in flow communication with the interior of the keg the other port and its member bore are out of flow communication with the interior of the keg, with both of said ports never in flow communication with a keg at the same time; and means for oscillating said valve member.

55 3. A beer barrel assembly including a keg and a dispensing faucet structure removably attached to one head of the keg; said structure including a body having a bore in it and having dual passageways opening into the bore for flow communication with the interior of the keg; a valve member oscillatable in said bore, said valve member having two axially spaced and extending bores in it, one opening through one end of said member and the other opening through the other end of said member and being out of communication with each other; said valve member also having ports from said member bores opening through the side surface of said member and being circumferentially spaced whereby one of said 60 ports is movable into and out of register with one of said dual passageways, and the other of said ports is movable into and out of register with the other of said dual passageways; the arrangement being such that when either port and its member bore are in flow communication with the interior of the keg the other port and its member bore are out of flow communication with the interior of the keg, with both of said ports never in flow communication with a keg at the same time; means for oscillating said valve member, and one end of said valve member being adapted to receive a hose connection for a supply of gas or air to the keg and the other end of said member having a beer discharge spout on it.

65 4. A beer barrel assembly including a keg and a dispensing faucet structure removably attached to one head of the keg; said structure including a body having a bore in it and having dual passageways opening into the bore for flow communication with the interior of the keg; a valve member oscillatable in said bore, said valve member having two axially spaced and extending bores in it, one opening through one end of said member and the other opening through the other end of said member and being out of communication with each other; said valve member also having ports from said member bores opening through the side surface of said member and being circumferentially spaced whereby one of said 70 ports is movable into and out of register with one of said dual passageways, and the other of said ports is movable into and out of register with the other of said dual passageways; the arrangement being such that when either port and its member bore are in flow communication with the interior of the keg the other port and its member bore are out of flow communication with the interior 75

of the keg, with both of said ports never in flow communication with a keg at the same time; means for oscillating said valve member, one end of said valve member being adapted to receive a 5 hose connection for a supply of gas or air to the keg and the other end of said member having a beer discharge spout on it, and said beer spout consisting of a plurality of sections, one of which is connected to the valve member and another of 10 which is connected to said first named section in a position to swing about an axis perpendicular to the axis of the valve member with a third section swiveled to the second mentioned section for swinging action in a plane parallel to the axis 15 of the valve member whereby said spout may be nested within the height of a keg chime when not in use.

5. A valve structure including a body having a bore through it and also having dual passageways opening into said bore, an oscillatable valve plug member in said bore, said valve member having two axially spaced and extending bores opening through opposite ends of said member, said member also having two substantially radial 20 ports from said member bores opening through the side surface of said member in axially and circumferentially spaced relation, one of said ports adapted to be moved into and out of register with one of said dual passageways and the other of said ports adapted to be moved into and 25 out of register with the other of said dual passageways as said valve member is oscillated, the

ends of said valve plug member being adapted to receive connection for flow communication through said member bores, and means for oscillating said valve member.

6. A dispensing faucet structure adapted for removable application to the head of a beer or like keg and having a jointed discharge faucet capable of nesting within the height of the keg chime when not in use and extensible over the chime for use, said structure having a bored body 10 and having dual passages opening into said bore for communicating with the interior of the keg, an oscillatable plug valve member in said bore having spaced and non-communicating bores opening through both ends of said member, said 15 member having a port communicating with one member bore and movable into and out of register with one of said dual passageways as said member is oscillated and having another port communicating with the other member bore and 20 movable into and out of register with the other of said dual passages, and a jointed discharge faucet having one section secured to one end of said member in communication with a member bore opening through that end and having an 25 other section swiveled to said first mentioned section to swing about an axis perpendicular to the member axis and a third section swiveled to said second section to swing in a plane parallel to said member axis. 30
